UNITED STATES PATENT OFFICE

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS

DESIGN FOR A SPOON OR ARTICLE OF ANALOGOUS NATURE

Application filed May 18, 1933. Serial No. 48,156. Term of patent 14 years.

To all whom it may concern:

Be it known that I, HAROLD E. Nock, a citizen of the United States residing at Newburyport, in the county of Essex and Commonwealth of Massachusetts, have invented a new, original, and ornamental Design for a Spoon or Article of Analogous Nature, of which the following is a specification, reference being had to the accompanying drawing forming a part thereof.

In the accompanying drawing Figure 1 is a view of one face of a spoon showing my new design; Fig. 2 is a side view of the outer end portion of the handle, on a larger scale; and Figs. 3, 4, 5 and 6 are sectional views

taken at the lines 3—3, 4—4, 5—5 and 6—6, respectively, of Fig. 1.

The design is delineated as embodied in the handle of a spoon but it is contemplated that the design may also be embodied in or applied, to the handles of forks, knives, servers and other analogous pieces of flatware which may form a part of a table service of uniform pattern.

I claim:

The ornamental design for a spoon or article of analogous nature, substantially as shown and described.

HAROLD E. NOCK.
